UNITED STATES PATENT OFFICE.

CORA E. TAYLOR, OF SPOKANE, WASHINGTON.

STEEL POST AND BASE FOR MAIL BOXES.

Application filed February 7, 1924. Serial No. 691,254.

My invention relates to a base for mail boxes and a supporting post for said base and more particularly to a base and post adapted to be constructed from structural metal elements.

The general object of my invention is to provide a combined post and base for mail boxes characterized by strength and simplicity of construction and the minimum number of elements employed.

A further important object of the invention is to provide in a structure of the class referred to a base which will firmly seat a mail box and permit of the box being firmly fastened in position.

The invention also has in view to provide a combined post and base for mail boxes constructed of elements so formed and so connected as to be readily assembled in knocked down form for shipping.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is an elevation of a post and base embodying my invention, the base being shown in side view, the mail box being indicated by dotted lines;

Figure 2 is an end elevation of the structure shown in Figure 1;

Figure 3 is a plan view of the combined post and base.

In carrying out my invention in accordance with the illustrated example, a post 10 is provided which in practice is formed in sections, the adjacent ends of which abut. Coupling angle pieces 12 are employed extending across the joint between the upper and lower base post sections secured in position by bolts 13 or equivalent means permitting of the post being shipped by parcel post in knocked down form and readily assembled and erected.

Each post is constructed of two uprights in the form of angle bars spaced from each other and connected by diagonal cross bars 11 and alternate cross bars 11 having opposite obliquity.

On the post 10 a base is secured. Said base comprises cross bars 14 of angle form, vertical flanges being disposed outside of the adjacent flanges. The upright angle bars of post 10 are so disposed that the horizontal flanges of the cross bars 14 will lie flush with the upper ends of the post uprights. Transverse bolts 15 or equivalent fastening means detachably secure the cross bars 14 to the post 10 at the center of said cross bars so that the cross bars project equally at opposite sides of the post.

On the cross bars 14 at the base longitudinal side bars 16 are laid to extend at their ends equal distances beyond the respective cross bars 14. The side bars 16 are in the form of angle bars and the horizontal flanges thereof form a seat for a mail box indicated at A, so that the mail box is received between the vertical flanges of the angle bars 16. Said angle bars 16 have set screws 18.

With the above described construction a post and base of maximum strength is attained, and the mail box is firmly seated and securely held in position.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claim.

Having thus described my invention, I claim:

In a post and base structure for mail boxes, a pair of upright angle bars, and oblique bars connecting said angle bars; together with cross bars secured at the approximate center thereof to flanges of said upright angle bars at the top of the latter, longitudinal angle bars crossing said transverse bars approximately at the ends thereof, said angle bars presenting horizontal flanges affording a seat for a mail box and presenting vertical flanges between which the lower portion of the mail box may be accommodated, and set screws in said vertical flanges of the longitudinal bars adapted to bind against the opposite sides of the mail box.

CORA E. TAYLOR.
